UNITED STATES PATENT OFFICE

WILLIS S. SHAFT, OF FARIBAULT, MINNESOTA, ASSIGNOR TO SHAFT-PIERCE SHOE COMPANY, OF FARIBAULT, MINNESOTA

CHANNELING KNIFE

Application filed January 25, 1927. Serial No. 163,491.

This invention appertains to channeling machines and more particularly to an improved knife for operating in conjunction with such machines.

5 One of the salient features of the present invention is the provision of a knife for use in conjunction with a shoe channeling machine for forming a combination inner and outer sole and for channeling the periphery 10 of the sole stock between the inner and outer soles.

Another object of the invention is the provision of a shoe channeling knife for operating in conjunction with certain portions of 15 a shoe channeling machine for beveling the extension of the outer sole of the combination inner and outer sole.

A further object of the invention is the provision of novel means on the knife for 20 simultaneously beveling the extension of the outer sole, beveling the periphery of the inner sole and for forming a channel between the inner and outer soles.

A still further object of the invention is to 25 provide a single knife operating in conjunction with a shoe channeling machine for channeling the stock and beveling the edges of the stock.

With these and other objects in view, the 30 invention consists in the novel construction, arrangement and formation of parts, as will be hereinafter more specifically described, claimed, and illustrated in the accompanying drawings, in which drawings:

35 Figure 1 is a top plan view of the improved knife,

Figure 2 is an edge elevation of the same,

40 Figure 3 is a fragmentary longitudinal section of the same taken on the line 3—3 of Figure 1 looking in the direction of the arrows,

45 Figure 4 is a transverse section of the knife taken on the line 4—4 of Figure 2 looking in the direction of the arrows, and showing the auxiliary cutting blade,

Figure 5 is an end elevation of the knife,

Figure 6 is a rear end elevation of the knife,

50 Figure 7 is an edge elevation of the knife

showing the opposite side thereof from Figure 2, and

Figure 8 is a perspective view of the entire knife.

Referring to the drawings in detail, where- 55 in similar reference characters designate corresponding parts throughout the several views the letter A generally indicates the improved knife, which comprises a shank 10 which is adapted to be connected with a knife block, (not shown) of a conventional shoe channeling machine. Extending forwardly from the shank 10 is a main blade 11. This blade is gradually tapered from one longitudinal edge toward the opposite edge to provide a longitudinally extending cutting face 12. The extreme outer end of the blade 11 which is remote from the shank 10 is likewise provided with a cutting edge 13 and this edge is gradually beveled as at 14 toward the non- 60 sharpened longitudinal edge of the blade. 65

The main blade 11 has associated therewith an auxiliary cutting blade 15 which extends transversely of the blade from one longitudi- 70

nal edge thereof to the other. This blade 15 is arranged slightly inward of the cutting edge 13 and has the edge adjacent to the cutting surface 12 provided with a cutting face or edge 16. It is to be noted that the auxiliary blade 15 extends at an angle to the blade 11 at a substantial forty five degree incline although this can be changed if desired. The auxiliary blade 15 also gradually increases in width toward the edge 16 to conform to the beveled face of the blade 11. The lower surface of the blade normally lies in a substantially horizontal plane and is provided with a plain flat surface which can be polished if preferred. The edge 13 is adapted to form the channels, while the edges 16 and 12 constitute means to form the outer sole and the beveled periphery of the inner sole. 85

90 From the foregoing description, it can be seen that I have provided a novel knife which will channel the periphery of a combination inner and outer sole and simultaneously with the formation of the channel bevel the edge of the inner sole. 95

Changes in details may be made without 100

departing from the spirit or the scope of the claim, but:

What I claim as new is:

A shoe channeling knife comprising a shank, a blade extending forwardly from the shank provided with a longitudinal cutting edge and a transversely extending cutting end, and an auxiliary blade formed on the upper face of the blade and extending transversely thereof adjacent to but spaced from the transversely extending cutting end, one end of the auxiliary blade being provided with a cutting edge adjacent to the longitudinal cutting edge, the auxiliary blade extending at an angle to the vertical and inclining away from the transversely extending cutting end, and said transverse cutting end being beveled toward the longitudinal cutting edge of the blade.

20 In testimony whereof I affix my signature.

WILLIS S. SHAFT.
